UNITED STATES PATENT OFFICE.

ARTHUR ROBERTS, OF EVANSTON, ILLINOIS, ASSIGNOR TO AMERICAN COKE & CHEMICAL COMPANY, OF CHICAGO, ILLINOIS, A CORPORATION OF MAINE.

COAL-DISTILLATION RETORT.

1,408,640.

Specification of Letters Patent. Patented Mar. 7, 1922.

Application filed September 15, 1916, Serial No. 120,351. Renewed February 13, 1920. Serial No. 358,432.

To all whom it may concern:

Be it known that I, ARTHUR ROBERTS, a citizen of the United States, residing at Evanston, in the county of Cook and State 5 of Illinois, have invented certain new and useful Improvements in Coal-Distillation Retorts, of which the following is a specification.

The present invention has to do with certain improvements in coal distillation retorts, and the features of invention herein disclosed relate particularly to the construction of so-called vertical retorts working on the continuous process principle. It will, 10 however, be apparent that certain of the features of invention are not limited to use in connection with vertical retorts, nor are the said features limited to use in connection with continuous process retorts. Inasmuch, 15 however, as numerous of the features herein disclosed are particularly adapted for use in connection with continuous process vertical retorts, I have found it convenient to illustrate and describe said features as used 20 in connection with this type of retort.

In continuous process vertical retorts, the raw material, usually in the form of coal, although not necessarily coal, is fed into the top portion of the retort, the coked material 25 being delivered from the bottom portion of the retort. As the coke or finished product is withdrawn from the lower portion of the retort, the coal or other material is fed in at the top, and works its way downwardly 30 through the height of the retort, the time necessary to reach the bottom portion of the retort being suitable for the complete prosecution of the carbonizing action desired. The duration of the carbonizing action may 35 be determined or regulated by the rate of travel of the material from top to bottom, and by the distance traversed through the carbonizing chamber.

As the material enters the upper portion 40 of the carbonizing chamber, it is quite cold, and its temperature must be increased to a maximum temperature depending upon the ultimate carbonizing action desired. This will be the temperature of the coke at the 45 time the carbonizing process is substantially completed. The coke at this stage will be red-hot or at any rate have an extremely high temperature, and before it can be discharged into the atmosphere it must be 50 cooled, either by a quenching operation or in

any other manner, because if the red-hot coke were to be brought into contact with the oxygen of the air, combustion would immediately commence, and there would be a very serious loss of fixed carbon and an 60 increase in the percentage of ash. Where the entire cooling of the coke is accomplished by a quenching operation, it is very evident that a serious loss of heat units is occasioned, because each pound of the red-hot 65 coke will contain a large number of heat units.

One of the objects of the present invention is to provide a construction of retort in which the temperature of the coal or other 70 raw material will be progressively increased as it travels through the length of the retort, by being brought progressively into contact with hotter and hotter portions of the heating walls until finally it reaches a point 75 where the heating walls are sufficiently hot to consummate the desired carbonizing action. In this way, the carbonizing action may be very nicely controlled and carried forward, while at the same time using a 80 minimum number of heat units for the heating of the walls, and thus economizing in the operation of the retort.

Another feature of the invention has to do with a construction of oven whereby a substantial portion, or for that matter by far the greater portion of the heat units of the coked material may be recovered from said material for useful application in the carrying forward of the carbonizing action with 85 in the retort, or other retorts. More particularly this feature of the invention has to do with the provision of a construction whereby all or a portion of the waste heat contained in the carbonized or coked material 90 may be used for the preheating of one of the constituent gases used in the heating of the walls of the oven. For example, the said waste heat may be used for the preheating of the air which goes to the burners. 100

Another feature of the invention has to do with the construction of the heating walls themselves, and in this connection it is desired to provide a heating wall which will very efficiently and effectively transfer the 105 heat from the hot gases into the heating walls. In Letters Patent of the United States, No. 1,132,685, which was issued to me March 23, 1915, for improvements in coke ovens, I have disclosed a construction 110

of heating wall in which provision is made for the transfer of heat between the gases and the wall by the impingement of the gases against portions of the heating wall to thereby very effectively improve the heat transference, and in my co-pending application for Letters Patent of the United States on improvements in the art of heating, Serial No. 43,753, which was filed August 5, 1915, I have disclosed and claimed certain features of the method of heat transference above referred to. In this present application, I have disclosed an improved form of notched block for use in the construction of the walls to thus still further improve the heat transference. Other features of the invention have to do with the provision of improved means for delivering the coal or other raw material into the carbonizing chambers, and improved means for removing the coked or carbonized material from the carbonizing chambers.

Other objects and uses of the invention will appear from a detailed description of the same which consists in the features of construction and combinations of parts hereinafter described and claimed.

Referring to the drawings:

Figure 1 shows a vertical cross section through a carbonizing chamber with its heating walls, including the contiguous heating walls of the two adjacent carbonizing chambers of the bench;

Fig. 2 shows a section similar to Fig. 1, with the exception that it is on larger scale;

Fig. 3 shows a section taken on the line 3—3 of Fig. 2, looking in the direction of the arrows;

Fig. 4 shows a section taken on the line 4—4 of Fig. 1, looking in the direction of the arrows;

Fig. 5 shows a horizontal section taken on the line 5—5 of Fig. 3, looking in the direction of the arrows;

Fig. 6 shows on enlarged scale a fragmentary horizontal section through a portion of a heating wall, including the improved notched block construction herein disclosed;

Fig. 7 shows a section taken on the line 7—7 of Fig. 6, looking in the direction of the arrows;

Fig. 8 shows a vertical fragmentary section taken on the line 8—8 of Fig. 7, looking in the direction of the arrows;

Fig. 9 shows in plan view one of the blocks of the form herein disclosed;

Fig. 10 shows a side elevation corresponding to Fig. 9; and

Fig. 11 shows a section taken on the line 11—11 of Fig. 10, looking in the direction of the arrows.

Referring now to Fig. 1, the three adjacent carbonizing chambers are designated by the numerals 12, 13, and 14. The upper

portion 15 of each chamber is narrower than its lower portion 16, so that, as the coking or carbonizing material descends and as it swells or expands, there will always be provided sufficient space to properly accommodate the material without jamming, and without the exertion of undue pressure on the walls.

Each carbonizing chamber is provided with heating walls designated in their entirety by the numerals 17 and 18. As shown by reference particularly to Figs. 3 and 4, these heating walls are of a width depending upon the width of the carbonizing chamber. Reference to Fig. 5 shows that while the carbonizing chambers are relatively narrow, still they are of considerable width so as to provide the desired cross sectional area. Reference to Fig. 4 will, furthermore, disclose that the carbonizing chambers are of greater width at the bottom than at the top so as to still further assist in securing a proper travel of the material undergoing treatment.

Above each carbonizing chamber is provided a hopper 19 for the accommodation of the coal, and a chute 20 leads downwardly from the hopper to the upper end 15 of the carbonizing chamber. It will be observed from Fig. 1 in particular that each hopper 19 with its chute 20 is offset to one side of the center line of the carbonizing chamber, this offsetting being accomplished by an intermediate casting or the like 21. This offsetting permits of the provision of one or more observation or manipulation holes 22 directly above and in line with the center line of the carbonizing chamber, through which holes the action within the carbonizing chamber may be observed, and through which holes rods or the like may be inserted for stirring up or adjusting the coal as it is delivered into the upper end of the carbonizing chamber. These holes will normally be closed by plugs 23, as shown in Figs. 1 and 4.

In order to control the delivery of coal into the carbonizing chamber, and for the prevention of a loss of distillate gas from the carbonizing chamber during its normal operation, I have shown a rotary valve 24 in each of the chutes 20. This rotary valve includes a casing of circular cross section within which rotates a cylindrical valve member. This cylindrical valve member is provided with oppositely disposed valve openings 25 and 26, so that, upon turning the valve member through 90 degrees, the chute will be placed in connection with the hopper 19 or will be completely isolated therefrom. The cylindrical valve member is provided with a sidewise extending shaft 27 having a pulley 28 over which may be passed a chain 29 for the convenient manipulation of the device.

The lower portion 16 of each carbonizing chamber communicates with a discharge member 30, the construction of which is shown in Figs. 1 and 4. Each of these discharge members has a chute 31, the lower surface of which curves to one side, so that the coked material delivered downwardly from the carbonizing chamber will be deflected over and into contact with a rotating 5 pick or breaker 32. This pick or breaker includes a shaft 33 having mounted thereon a series of picks 34 in sets, the picks of the different sets being consecutively mounted on the shaft at slightly different 10 angular positions, so that the pick points will bear a spiral relationship with respect to the shaft as the observer moves his eye along the shaft from one end to the other thereof. The shaft 33 may be rotated in any 15 convenient manner as by means of a pulley 35. By the use of the construction thus disclosed, the picking or breaking operation will proceed consecutively at different portions of the carbonizing mass, instead of 20 simultaneously at all portions thereof, thus making it easier to carry forward the breaking operation, inasmuch as the breaking force will at each instant be limited to some particular portion of the carbonizing mass. 25

The lower end 36 of the chute is tapered in size and terminates in the form of a spout. Beneath this spout is swingingly mounted a valve member 37, the same swinging on a horizontal axis 38. This valve 30 member is of segmental formation, its end portions being closed by the end plates 39 and 40. The valve member normally stands in the lowered position shown in Fig. 1, but it may be swung to one side by the use of 35 a handle 41 when it is desired to discharge the coke. When the valve member stands in the closed position, it may be filled with water, if desired, for the purpose of providing a water seal to thereby prevent the entrance of air into the carbonizing chamber, or the wastage of distillate gas from said 40 chamber.

The distillate gases are discharged from the carbonizing chamber through the ports 42 and 43 located near the upper portion 45 of the carbonizing chamber, as shown in Fig. 4. Each of these ports communicates with an angular casting 44, by means of which the gases are delivered upwardly to the connections 45. From said connections 50 the gases find their way to the hydraulic mains 46, or to any other suitable discharge pipes. The connections 44 may be easily cleaned by the insertion of rods or the like 55 through their end portions 47, which portions are normally closed by the caps 48.

I will now explain in detail the construction of the heating walls herein disclosed. The carbonizing action commences in the 60 upper portion of the carbonizing chamber

and terminates substantially at the point indicated by the numeral 49 in Fig. 1. As the material descends below the point 49, it is desirable to cool the same, so that by the time it reaches the picks or breakers, it will 65 be relatively cool. On the other hand, the heating walls just above the point 49 should have a maximum temperature sufficient to complete the carbonizing action and distill the volatile constituents to the extent desired by the operator. I have, therefore, shown a construction of heating wall in 70 which the temperature may be successively increased in its different portions, being maximum substantially at the point 49, and 75 by means of which the material descending 80 below the point 49 may be cooled, the heat thus given off being effectively used for the preheating of the air.

For this purpose, I divide the heating 85 walls between the points 15 and 49 into a series of zones, the temperature of each zone being regulated to the desired point. In the particular construction there are three 90 of these zones numbered, respectively, 50, 51, and 52, although manifestly a greater or less number of zones may be used as desired. Each zone is provided with a mesh-work of impingement passages, or with any other suitable form of heating passages, so 95 that the heating gases traversing the said zone will effectively transfer heat to the wall. As previously explained, these heating walls are shown particularly as operating on the impingement principle, but manifestly as 100 far as the feature of division into different zones of different temperature is concerned any other suitable form of heating wall might be adopted.

The zones thus described are shown as 105 being divided from each other by partitions 53 and 54, the partition 55 which delimits the lower edge of the zone 52 being substantially at the point 49.

Each of the zones is illustrated as being 110 built up from rows of notched blocks, the construction of which will be presently explained in detail. An air riser 56 extends upwardly adjacent to the pair of heating walls, the said riser delivering air to a series 115 of burners or combustion points 57 for each heating wall through the connections 58, best shown in Figs. 3 and 5. A gas riser 59 extends upwardly adjacent to each pair of heating walls, and delivers gas to each of 120 the chambers 57 through a series of gas connections 60. Consequently, the combustion commences in the chambers 57 and the heating gases then travel sidewise towards the other side of the heating wall. A valve 125 61 is mounted in each of the connections 60, so that the gas delivery to each one of the chambers 57 may be very nicely regulated according to the heating effect desired.

Adjacent to the other side of each pair 130

of heating walls is a downcomer 62 for the delivery of spent gas to a pipe or tunnel 63 which extends along the length of the bench of ovens, and a damper or the like 64 5 may be provided for controlling the delivery of spent gas from each of the connections 62 to the pipe or tunnel 63. At the discharge side of each heating wall there is a series of chambers 65, which chambers 10 communicate with the downcomer 62 through the connections 66, so as to deliver the spent gas to the downcomer.

Manifestly by proportioning the heating structures in the different heating zones, and 15 by properly regulating the various valves 61, the temperatures established in the different zones may be such as to cause a progressive rise of temperature as the material descends in the retort. If desired, the temperature may be substantially constant 20 throughout each of the zones delimited by the partitions 53, 54, and 55, or the temperatures may progressively increase from top to bottom of each of the so-called zones. 25 This progressive increase in temperature may be accomplished, for example, by proper regulation of the valves 61, or by proportioning the notched blocks in the original construction of the wall. The point 30 is that the temperatures in the heating wall increase in the direction of travel of the mass, said travel, in the particular construction illustrated, being from top to bottom, although manifestly it might also be from 35 side to side, or in any other desired direction.

Beneath the point 49 the walls are shown as being recuperating walls adapted to pre- 40 heat the air or any other constituent gas for combustion. The preheating is shown as being a preheating of the air, although this is done largely as a matter of convenience. The air comes in the first place from a pipe or tunnel 67. Each heating wall below the 45 point 49 or below the partition 55 is provided with a series of meshwork of impingement passages leading from the point 68 to the point 69, the air traveling across the wall beneath a partition 70, and then 50 upwards and back above the partition 70 to the point 69. At this point it enters the lower end of the riser 56. In this way the air is preheated by the use of heat which would otherwise be wasted in the hot coke 55 or other material.

Referring now to Figs. 6 to 11 inclusive, I will explain more in detail the particular form of notched block therein illustrated. The block is of substantially rectangular 60 form, its central side portions being cut away as shown at 71 and 72. Its corners are cut away as at 73, 74, 75, and 76. The lower central portion 77 of the block depends below its end portions, so that the portions 77 65 of each block extend into the space between

the notches 73 and 74 of the blocks of the next lower course, when the blocks of the various courses are so set as to break joints. In this way, the gases traveling along the wall are caused to deflect around the portions 77, so that it is impossible for the gases to travel straight across the wall and without being subjected to any impingement action. By the use of this arrangement, it is possible to cause the gases to travel in a 75 zigzag manner with respect to the blocks, even when the gases are traveling parallel to the courses of blocks instead of transversely of said courses.

The end portions of the blocks are set 80 together so as to completely enclose the zig-zag impingement passages, in the manner shown particularly in Figs. 5 and 6. While the blocks are shown as dove-tailing together, and also as key-stoning together, still 85 it is evident that the end portions of the blocks may be of any suitable form according to the particular requirements of the case.

Reference particularly to Fig. 1 will dis- 90 close a pipe 78 connected into the chute 31 by way of a connection 79 having a valve 80. The pipe 78 with the connection 79 and valve 80 provide means for introducing steam, oil, or other material into the hot coke or car- 95 bonized mass descending through the chute 31. It is well understood that when steam, preferably in dry condition, is directed against a mass of red hot carbon, the steam will be broken up or decomposed with the 100 liberation of hydrogen and the production of carbon monoxide. This process is known as a water-gas process. The reaction thus taking place results in a tremendous absorption of heat, thereby tending to cool the 105 coke. Inasmuch as the water-gas thus generated has a very much higher thermal value than the original coal or coke, it follows that all or a portion of the heat of the red hot carbonized mass is transformed by a 110 chemical reaction into a static or potential condition, the heat which would otherwise be wasted in the red hot coke or carbonized material being recovered in the form of gases which are potentially capable of giving off, when burned, substantially all of the 115 heat thus absorbed from the red hot coke.

Consequently, when steam is introduced in the manner indicated from the pipe 78 not only is the coked or carbonized mass cooled 120 which is in itself a very desirable result, but its heat which would otherwise be wasted is largely recovered in the manner indicated.

Or sometimes it may be desirable to inject oils through the pipe 78 and connection 79, 125 which oils, upon contact with the red hot mass, will be split or broken up, thereby enriching the gas delivered from the carbonizing chamber, and also resulting in a cooling of the carbonized material. There- 130

fore, this feature of my invention contemplates the introduction of liquid or fluid material into the carbonizing chamber at a point where a cooling of the carbonized material may be secured, to thereby cool said material, and in many cases recover all or a portion of the waste heat substantially as indicated.

Where, in this specification and the claims 10 to follow, I have spoken of the "continuous process principle", or a "continuous process retort", or have used the word "continuous", it will be understood that I contemplate equally the use of the features of invention 15 also in cases where the action is not strictly continuous, but is of the semi-continuous type as distinguished from the so-called "intermittent" type.

While I have herein shown and described 20 only a single form of construction embodying the features of my invention, still it will be understood that I am not limited to the same, except as I may limit myself in the claims.

25 I claim:

1. A continuous process vertical distillation retort comprising a pair of heating walls enclosing a carbonizing chamber between them, said walls being closer together 30 in their upper portions than in their lower portions to thereby provide a tapering width for said chamber, each heating wall comprising blocks laid up in horizontal courses, each block being recessed in its central portions to provide a series of interconnected 35 gas passages extending in zigzag fashion across the interior of the wall, means for isolating the passages so constituted from each other in horizontal zones extending 40 across the wall, to thereby prevent intercommunication of heating gases between the passages of different zones, a plurality of fuel nozzles for delivering fuel gas into the heating passages at one edge of each wall, there 45 being passages for the delivery of air into the wall adjacent to said nozzles for combustion purposes, means for independently controlling the supply of fuel to all of the nozzles, there being air passages in the lower 50 portion of each wall, means for delivering fresh air into said passages for preheating purposes, and means for delivering heated air from said passages to the air connections aforesaid, for preheating purposes substantially 55 as described.

2. A continuous process vertical distillation retort comprising a pair of vertical heating walls separated from each other to provide a carbonizing chamber of desired 60 width at each point, vertical end closures between the end portions of said walls, each heating wall having on its interior a plurality of groups of interconnected passages for heating gases extending across its por-

tion in zigzag fashion from one edge of 65 the wall to the other edge thereof, the passages of each set being separated from those of the other side to thereby provide distinct zones, means for delivering combustible mixture into the heating passages at one edge 70 of each zone, means for controlling the rate of admission of such mixture into each zone independently of the other zones, there being a plurality of preheating passages in the lower portion of each heating wall, means 75 for delivering combustible constituent thereto for preheating purposes, preheated constituent from such passages to the aforementioned combustible mixture delivering means, means for delivering substantially as 80 described.

3. A continuous process vertical distillation retort comprising a pair of vertical heating walls separated at all points a distance from each other according to the desired width of the carbonizing chamber, there being on the interior of each heating wall a series of interconnected passages for 85 heating gases extending across the wall in zigzag fashion from one edge thereof to the other edge in substantially horizontal direction, and means for delivering the combustible mixture into said passages at one edge of each wall, and at all points under the control of the operator, substantially as 90 described.

4. A continuous process vertical distillation retort comprising a pair of vertical heating walls, there being on the interior of each heating wall a series of interconnected 100 passages extending across the wall in zigzag fashion from one edge thereof to the other edge in substantially horizontal direction, means for delivering combustible mixture into said passages at one edge of each 105 wall, means for delivering carbonaceous material into the upper portion of the chamber, means for withdrawing carbonized material from the lower portion of the chamber, and means for delivering distillate gas from the 110 upper portion of the chamber, substantially as described.

5. A continuous process vertical distillation retort comprising a pair of vertical heating walls, there being on the interior of 115 each heating wall a series of interconnected passages extending across the wall in zig-zag fashion from one edge thereof to the other edge in substantially horizontal direction, and means for delivering combustible mixture into said passages at one edge of the wall, substantially as described.

6. A continuous process vertical distillation retort comprising a pair of vertical heating walls, there being on the interior 125 of each heating wall a series of interconnected passages extending across the wall in zig-zag fashion in a substantially horizontal di-

rection, and means for delivering combustible mixture into said passages at one edge of the wall, substantially as described.

7. In a vertical distillation retort the combination of vertical heating walls, each having on its interior a series of interconnected passages extending across the wall in zig-zag fashion in a substantially horizontal di-

rection, and means for delivering combustible mixture into said passages at one side 10 of the wall, substantially as described.
